ATTORNEY

UNITED STATES PATENT OFFICE.

JOSEPH DAVING, OF NEW YORK, N. Y.

DESIGN FOR A WATCHCASE OR LOCKET.

58,021.

Specification for Design.

Patented May 31, 1921.

Application filed May 31, 1918. Serial No. 237,645. Term of patent 3½ years.

To all whom it may concern:

Be it known that I, JOSEPH DAVING, a citizen of the United States, residing in the borough of Manhattan, in the county, city, and State of New York, have invented a new, original, and ornamental Design for Watchcases or Lockets, of which the following is a specification, reference being had to the accompanying drawing, forming part thereof.

Figure 1 of the drawings is a plan view of a watch case or locket showing my new design:

Fig. 2 is a side view thereof.

I claim:

The ornamental design for a watchcase or locket as shown.

JOSEPH DAVING.
